ABSTRACT: A batch of an oil-in-water emulsion such as milk or a milklike substance is stabilized by the addition of a viscosity increasing agent, a portion of the batch is analyzed to determine the fatty content thereof and the remainder of the stabilized batch is then utilized as a reference standard for checking and calibrating apparatus which is used to determine the fatty content of such emulsions by the light transmission characteristics thereof.

DETERMINING THE FAT CONTENT OF MILK

This invention relates to a preparation for controlling and adjusting an apparatus of the type used for determining the fatty content of an oil-in-water emulsion by measuring the physical properties of the emulsion such as sound or light transmission, a process for preparing said preparation, and a method for its application.

The known art comprises apparatus which determine the fatty content of an oil-in-water emulsion by measuring the physical properties of the emulsion such as sound or light transmission, but generally such apparatus are not stable over prolonged periods and require control and adjustment from time to time. Up to now this control has required complicated and time-consuming laboratory methods, and the adjustment could not therefore be made continuously, which has reduced the applicability of the apparatus.

The aim of the present invention is to provide a preparation having stabilized physical properties, which preparation, after determination of its fatty content in an accurately adjusted apparatus or by conventional analytic methods, can be used for continuous control and adjustment or other similar apparatus.

This has been achieved by the preparation according to the invention which consists of an oil-in-water emulsion admixed with a stabilizing agent for maintaining the emulsified state.

As the said apparatus are usually intended for determining emulsions of a certain type and would render inaccurate results for emulsions of different types the preparation according to the invention may advantageously contain an emulsion of the same type as normally determined in the apparatus.

As stabilizing agent may be used any agent capable of maintaining the emulsion in a stable state at room temperature and below, but which may be restored to the normal liquid state of the emulsion, for instance by changing the pH value of the preparation or by heating. According to the invention the preparation may conveniently contain a gelling agent of the type which causes the preparation to set at room temperature and below but restores the normal liquid state of the emulsion on being heated. Examples of such gelling agents are gelatine, carrageenanes, pectins, and agar-agar.

According to the invention gelatine has proved particularly suitable as gelling agent, as the preparation made therewith possesses a good gel consistency without any tendency to separation of liquid and after heating to melting temperature has a consistency approximately like that of the original emulsion.

The present invention is particularly intended for use in connection with the apparatus for rapid determination of the fatty content of milk developed by applicants in the present application and sold under the name of Milko-Tester. The determination of the fatty content in a Milko-Tester is based on the ability of the milk-fat globules to diffuse and absorb part of the light transmitted through a milk sample. The principle of determining the fatty content is a measurement of the amount of light capable of penetrating a milk sample homogenized and diluted with a special liquid containing inter alia protein-dissolving tetrasodium salt of ethylene diamine tetraacetate (trade name: Versene). The more fat globules the milk contains the more the light will be diffused. By measuring the light transmitted through milk samples whose protein has been dissolved values are obtained which bear a certain relation to the fatty content of the milk sample. The principal reason why this relation is not complete is the phenomenon known from homogenized milk wherein the finely divided fat globules make the milk whiter in color because the many minute fat globules of the homogenized milk cause a greater diffusion of light than the smaller number of large fat globules of the nonhomogenized milk, and therefore milk samples having the same fatty content will produce different results when measured by light transmission where the size distribution of the fat globules varies. To equalize this source of error the milk is homogenized in four steps in the Milko-Tester.

The actual measuring of the light transmitted through the prehomogenized and diluted milk samples takes place while

the samples pass a cuvette which is hit by light having a wavelength of about 600 nm. The penetrating light is registered by a photoelectric cell connected to a galvanometer wherein the scale is divided directly into fat percent.

5 A disadvantage in using the Milko-Tester is that previously it was not possible to control accurately and rapidly whether the reading of the apparatus was correct. The only possibility of control was to determine by traditional analytic methods the fatty content of a selection of the milk samples analyzed by the Milko-Tester.

For several reasons this method is inexpedient. The traditional analytic methods are laborious, and it requires time before the results are available. The Ross-Gottlieb method

15 produces the most accurate results, but they are not available until the day after the analysis has been commenced. The results cannot therefore be used for a continuous control or adjustment, but only for correction of the previous day's Milko-Tester results. The Gerber method is less accurate, but the results are available substantially earlier and may therefore be used for a fairly reliable adjustment and current control of the Milko-Tester. Both methods require skilled staff and extensive laboratory equipment, which is unfortunate as the very idea of the Milko-Tester was to avoid this. Finally, as

20 a disadvantage should be mentioned the necessity of using a comparatively large number of milk samples for controlling the Milko-Tester.

One embodiment of the preparation according to the invention has proved to be particularly suitable for rapid control

30 and adjustment of the Milko-Tester. As the preparation in many respects was to act as a milk sample it was natural to base it on milk. As gelling agent gelatine was found to be particularly advantageous as its gelling ability is completely neutralized at temperatures above about 40° C., so that the preparation may without difficulty pass through the Milko-Tester, which itself heats the milk to 60° C. In accordance herewith a specific embodiment of the preparation according to the invention is characterized in that it consists of milk

35 wherein at least 0.5 percent by weight of gelatine is dissolved.

40 To make the preparation resistant to microbiological decomposition it may expediently contain preservatives. Among the preservatives sodium benzoate alone was found to be incapable of giving the preparation adequate keeping qualities. It was then tried to use also a substance having a strong bacteriostatic activity. According to the invention it has been found to be particularly expedient together with the benzoate to use a quaternary ammonium compound, for instance alkylidimethylbenzylammonium chloride (trade name: Rodalon) in a concentration of about 0.1 percent active substance in the preparation.

45 The preparation according to the invention may generally be prepared by a process which according to the invention is characterized in that an oil-in-water emulsion is admixed with a stabilizing agent dissolved in the emulsion during heating, whereupon the mixture is cooled to form a gel.

50 For preparing the particular embodiment of the preparation especially suitable for controlling and adjusting the Milko-Tester milk is used as emulsion and gelatine as stabilizing agent. A preferred embodiment of the process according to the invention is characterized in that milk is heated to about 40° C. or above whereupon at least 0.5 percent by weight of gelatine is added while stirring and the solution formed is bottled if desired after filtration.

55 With a view to the keeping qualities of the preparation it has furthermore been found to be expedient to subject the milk to low-temperature pasteurization and, to prevent the fat from rising during the pasteurization, to start with a mild homogenization of the milk.

60 The application of the preparation according to the invention for controlling and adjusting for instance the Milko-Tester may be carried out as follows:

A few bottles of each production are drawn for determining the value which it is desired to obtain for the contents of each bottle from the production in the Milko-Tester. The selected

bottles are placed in a water bath at 40° C. until the gel has melted (about 5 minutes), whereupon the contents of each bottle is measured 2 or 3 times on a correctly operating Milko-Tester. The average value is calculated, and the other bottles from the production are marked with this value. The accurate determination of the contents may, if desired, be made by using one of the conventional analytic methods.

The other bottles may now be used for controlling and adjusting other Milko-Testers. The method is the following:

A bottle is placed in a water bath as described above, and 2 or 3 readings are taken on the Milko-Tester to be controlled.

readings on the Milko-Tester were taken 2, 3, 5, 7, 12, 14, 20, and 26 days after preparing the two batches of the preparation.

Of the four Milko-Tester results of each bottle the first one was discarded with a view to possible errors due to carryovers. The averages of the other three results are listed in table 1.

TABLE 1

Average of the Milko-Tester results for two batches of preparation, each kept in bottles for different periods of time at 8° C.

	Number of days stored							
	2	3	5	7	12	14	20	26
Batch 1: Average of individual bottles	3.69	3.67	3.65	3.66	3.65	3.66	3.61	3.64
	3.65	3.63	3.63	3.63	3.65	3.63	3.64	3.62
	3.63	3.63	3.64	3.63	3.62	3.65	3.65	3.64
	3.62	3.66	3.64	3.67	3.64	3.64	3.66	3.63
	3.67	3.64	3.63	3.66	3.64	3.65	3.63	3.64
	3.64		3.64			3.66	3.63	3.64
	3.64		3.63			3.65	3.65	
	3.64		3.63			3.63	3.63	
	3.65		3.64			3.65	3.66	
	3.63		3.67			3.64	3.65	
Daily average	3.65	3.66	3.64	3.65	3.64	3.65	3.64	3.63
Batch 2: Average of individual bottles	4.01	4.02	4.00	4.00	4.01	4.02	4.02	4.01
	3.99	4.02	4.00	4.00	4.00	4.00	4.02	3.99
	3.99	4.00	4.01	3.99	4.00	4.00	4.02	4.00
	3.98	4.01	3.99	3.97	4.00	4.01	4.01	3.99
	4.01	4.01	3.98	4.00	3.98	4.03	3.99	4.00
	3.98			4.00		4.01	3.99	
	3.98			3.99		4.02	4.01	
	4.00			4.00		3.99	3.99	
	3.95			4.00		3.97	3.99	
	3.96			4.00		3.99	4.00	
Daily average	3.99	4.01	4.00	4.00	4.00	4.00	4.00	4.00

If the average result differs from the value stated on the bottles, this variation may be used as correction for the results of the milk samples, and the Milko-Tester may be adjusted to show the value stated.

EXAMPLE

Preparing the preparation:

1: 12 liters of cold milk are admixed with 3 grams of sodium benzoate per liter.

2: The milk is heated to 50° C. and homogenized at at least 50 atm.

3: Low-temperature pasteurization (30 minutes at 63° C.).

4: The 40°-50° C. warm milk is admixed with 20 grams of gelatine per liter. Stirring.

5: Filtration through a fine-mesh strainer.

6: Gradual admixture during stirring of 50 ml. 2 percent Rodalon (or other quaternary ammonium compound).

As appears from the table, the stress has been on determinations shortly after and 1, 2, and 3 weeks after the preparation of the batches. The additional samples were used for supplementary measurements. The daily average is plotted in respectively FIG. 1 and FIG. 2 of the drawing, and it will be seen that the variations are very small and occur within a very restricted interval, and the preparation must therefore be considered very stable after storage at 8° C. for more than 3 weeks.

To get an idea of the variation from bottle to bottle a calculation was made of the standard deviation from respectively the daily and the total average for the days where readings were taken of many bottles, and for all the bottles from each batch collectively. These results are listed in table 2.

TABLE 2

Average values and corresponding standard deviations calculated on the basis of table 1.

TABLE 2. AVERAGE VALUES AND CORRESPONDING STANDARD DEVIATIONS CALCULATED ON THE BASIS OF TABLE 1

	Number of days stored				All 60 results
	2	7	14	20	
First batch	3.65±0.021	3.65±0.018	3.65±0.012	3.64±0.015	3.64±0.017
Second batch	3.99±0.020	4.00±0.011	4.00±0.018	4.00±0.016	4.00±0.016

7: Tapping into bottles of 200 ml.

8: Cooling in a water bath to 8°-10° C. Cool storage. Notes:

Raw milk of good bacteriological quality is used. It is important that the admixture of Rodalon takes place gradually and during stirring as otherwise precipitation may occur in the milk.

Testing the preparation

To test the suitability of the preparation for controlling and adjusting the Milko-Tester it was examined whether a series of different samples from the same production were so uniform and kept so well that after storage for different periods of time they would give the same reading on the Milko-Tester. For the testing two separate batches of the preparation were prepared according to the above directions and each tapped into 60 200 ml. bottles.

At few days' intervals a number of bottles from each batch were taken out from the cool store. After melting the gel four readings of each bottle were taken on the Milko-Tester. The

Table 2 shows that the standard deviation is between one and two hundredths percent of fat, which is within the standard deviation for repeated measurements of the same milk sample with the Milko-Tester. Therefore there has been no significant difference between the results of the individual bottles from the same batch of preparation.

The testing did not include examinations of the keeping qualities of the preparation when stored at temperatures above 8° C., but the stability of the gel up to its melting point at 30°-32° C. and the effect of the preservation made it probable that the samples would withstand storage for a shorter or longer period of time also at temperatures above 8° C.

No attempts were made to determine the fatty content of the preparation by the traditional analytic methods, and it is probably inadvisable to employ these methods for determining the values desired for the samples of the preparation on the Milko-Tester as homogenized milk samples are known to produce Milko-Tester results which differ from the cor-

responding results of the Gerber and Rose-Gottlieb determinations. The safest method of determining the values desired for the preparation on the Milko-Tester will therefore be the method according to the directions stated.

The testing proved that by following the directions it was possible to prepare series of samples which were so uniform and kept so well when stored at 8° C. that the samples showed the same result on the Milko-Tester more than three weeks after their preparation.

Later two batches of preparation were prepared by a procedure differing slightly from the aforesaid, namely in that the admixture of Rodalon was made first simultaneously with the admixture of benzoate, and the low-temperature pasteurization was performed last on the filled and sealed bottles. This amended procedure should have no effect on the results rendered by the preparation on the Milko-Tester, but should improve its resistance to microbial decomposition. Bottles from the said batches were stored for four months at room temperature with no visible signs of any change.

We claim:

1. Method of calibrating an apparatus for determining the fatty content of milk by measuring light transmission

therethrough comprising preparing a mixture of milk and approximately one-half to two percent gelatin, dividing said mixture into a plurality of samples, subjecting a number of said samples to an accurate determination of the fatty content thereof, marking the remaining number of said samples with the fatty content determined from said accurate determination, and calibrating such apparatus by measuring the light transmission through at least one of said marked samples.

2. Method defined in claim 1 further comprising heating said marked samples to recover the normal liquid state of the mixture before measuring the light transmission therethrough to calibrate the apparatus.

3. Method of preparing a sample for calibrating an apparatus for determining the fatty content of milk by measuring light transmission therethrough comprising, preparing a mixture of milk and approximately one-half to two percent gelatin, dividing said mixture into a plurality of samples, subjecting a number of said samples to an accurate determination of the fatty content thereof and marking the remaining number of said samples with the fatty content determined from said accurate determination.
